UNITED STATES PATENT OFFICE.

JOHN C. BROOKS, OF MIDDLETOWN, CONNECTICUT, ASSIGNOR TO
DRAPER COMPANY, OF HOPEDALE, MASSACHUSETTS, A CORPO-
RATION OF MAINE.

LOOM-SHUTTLE.

SPECIFICATION forming part of Letters Patent No. 767,379, dated August 16, 1904.

Application filed May 19, 1904. Serial No. 208,691. (No model.)

To all whom it may concern:

Be it known that I, JOHN C. BROOKS, a citizen of the United States, residing at Middletown, in the county of Middlesex and State of Connecticut, have invented an Improvement 5 in Loom-Shuttles, of which the following description, in connection with the accompanying drawings, is a specification, like characters on the drawings representing like parts.

10 The present invention relates to loom-shuttles, and especially to the so-called "self-threading" loom-shuttles, and has for one of its objects the production of a shuttle of this type provided with novel means for retaining 15 the weft-thread in the thread-passage leading to the delivery-eye, and for another object the production of a loom-shuttle of this type provided with novel means for breaking or severing the filling upon the occurrence of a 20 float in the warp, thereby causing the prompt stoppage of the loom and avoiding any "pick-outs."

My novel means for retaining the filling in the thread-passage comprises a gate normally 25 closing said passage, but constructed to be opened by the thread as the latter enters therein.

The thread-parting mechanism comprises a cutter coacting with the gate to sever the 30 thread and rendered operative by the occurrence of a float in the warp.

While the invention has been illustrated in connection with a self-threading shuttle, it is also applicable to other types of shuttles, and 35 it can be used with equal facility in a common shuttle operated in a non-replenishing loom.

In the drawings, Figure 1 is a plan view of 40 a portion of a shuttle having my improvements applied thereto. Fig. 2 is a side view of the shuttle, a part thereof being broken out to better illustrate the construction of the device. Fig. 3 is a section on the line $\alpha\alpha$, Fig. 1. Fig. 4 is a detail of the parts hereinafter described.

45 B represents a shuttle-body having the usual side delivery-eye (not shown) and the longitudinal opening B' to receive the filling-carrier or bobbin B^X. These parts are of any suitable or usual construction. As herein

illustrated, said shuttle B is provided with 50 a threading-block T, having a longitudinal thread-passage t, which connects with another passage leading to the delivery-eye, as usual in these self-threading shuttles. The thread-passage T has an open throat 3, through which 55 the thread passes as the shuttle is threaded. Heretofore in these self-threading shuttles it has been common to make the throat 3 comparatively narrow and provide one end of it with a stationary guard, which prevents the 60 thread from being thrown out of the thread-passage after it has once been inserted. In my improved construction I do away with this stationary guard and make the end of the throat 3 nearest the bobbin comparatively 65 wide, as shown at 4, Fig. 1, and provide a suitable automatically-operating gate which normally closes the throat of the thread-passage, but permits a thread to enter therein when the 70 shuttle is threaded. In the present form of my invention this gate is designated by 5, and it comprises a member pivotally mounted on one wall 6 of the threading-block and having one arm 7 thereof projecting across the throat of the thread-passage, as best seen in Fig. 3. 75 I prefer to make this gate in the form of a gravity-actuated gate, and for this purpose extend the end 8 thereof through the wall of the threading-block, said wall being recessed for this purpose. The end 8 acts as a counterweight to hold the gate normally in the 80 position shown in Fig. 3. Said end 8, however, is only slightly heavier than the end 7, the difference in weight between the two ends of the gate being so small that as the thread 85 enters the throat 3 and bears against the gate the tension on said thread will swing the end 7 of the gate downwardly and away from the wall 14^a of the threading-block, thus opening the throat of the thread-passage. The thread 90 then passes off from the end 7 of the gate and the latter closes by its own weight and holds the thread in the thread-passage t.

When the automatically-operating gate is employed for holding the thread in the thread-passage, the throat 3, leading to said thread-passage, may be made wider than is possible where a stationary guard is employed and the 95

operation of threading the shuttle thus made more sure.

Coacting with the gate 5 is a suitable device which operates to part or sever the weft-thread when a float occurs in the warp. In the form of my invention herein illustrated such means comprises a lever 10, pivotally mounted on the side wall of the shuttle, as at 11, and having one end 12 shaped to extend 10 normally slightly above the side wall of the shuttle-body. The other end of said lever is bent inwardly, as at 13, and extends through a suitable aperture in the wall 6 of the threading-block, said bent end of the lever being 15 formed with a cutting-blade 14, which lies in a recess in the shuttle immediately below the thread-passage *t*.

I prefer to make the end 7 of the gate with the two branches or arms 15 and to so locate 20 said gate with reference to the cutting-blade 14 that said blade lies directly below the space between said arms.

The counterweight 8 is directly above the portion 13 of the lever 10, as best seen in 25 Fig. 4.

The float-detecting lever 10 is normally held in the position shown in Figs. 2 and 3 either by making the end 13 thereof sufficiently heavy to overbalance the projecting end 12 or 30 by using a suitable spring or its equivalent.

The parts, as shown in Figs. 2 and 3, are in their normal position, from which it will be seen that after the shuttle is threaded the thread 16 can pass freely through the thread-passage to the delivery-eye as the shuttle is shot back and forth through the shed. When, however, the shuttle in passing through the shed encounters a float, and is thereby lifted to make an overshot, the warps above engage 40 the end 12 of the float-detecting lever, and thereby raise the end 13 thereof, said lever swinging about its pivot 10. The upward movement of the end 13 of said lever brings said end against the arm 8 of the gate, raises 45 said arm and swings the arm 7 downwardly, said arm 7 coöperating with the knife or blade 14, which passes up between the two branches of the arm to sever or cut the weft-thread. Upon the cutting of the weft-thread the loom 50 is promptly stopped by any suitable mechanism employed for that purpose.

Manifestly the float-detecting and thread-severing mechanism may be applied to any common shuttle as well as to one provided 55 with an automatic self-threading device.

My invention is not limited to the details of construction herein illustrated, as these may be varied in many ways without departing from the spirit of the invention expressed in 60 the appended claims.

Having described my invention, what I claim as new, and desire to secure by Letters Patent, is—

1. In a loom-shuttle having a delivery-eye, a 65 threading-block having a thread-passage lead-

ing to said eye, and a pivoted gate normally closing said passage and constructed to be opened by the thread entering the same.

2. In a loom-shuttle having a delivery-eye, a 70 threading-block having a thread-passage leading to said eye and a gate normally closing said thread-passage and held in its normal position by gravity, said gate constructed to be opened by the thread entering said passage.

3. In a loom-shuttle having a delivery-eye, a 75 threading-block having a thread-passage leading to said eye, a gate pivoted to one wall of said threading-block and normally closing said thread-passage, said gate being held in its closed position by gravity and constructed to 80 be opened by the thread entering said passage.

4. In a loom-shuttle having a delivery-eye, a 85 threading-block having a thread-passage leading to said eye, a gate normally closing said passage but constructed to be opened by the 90 thread entering the same, and means coöperating with the gate to part the thread upon the occurrence of a float in the warp.

5. In a loom-shuttle having a delivery-eye, a 95 threading-block having a thread-passage leading to said eye, a pivoted gate normally closing said passage and constructed to be opened by the thread entering the same, and means coöperating with said gate to part the thread upon the occurrence of a float in the warp. 95

6. In a loom-shuttle having a delivery-eye, a 100 threading-block having a thread-passage leading to said eye, a gate pivoted to one wall of said threading-block and normally closing said thread-passage, said gate being held in its closed position by gravity and constructed to be opened by the thread entering said passage, and means coöperating with said gate to part the thread upon the occurrence of a 105 float in the warp.

7. In a loom-shuttle having a delivery-eye, a 110 threading-block having a thread-passage leading to said eye, a gate normally closing the entrance to said passage but constructed to be opened by the thread as it enters the latter, and automatic means to sever the thread upon the occurrence of a float in the warp. 110

8. In a loom-shuttle having a delivery-eye, a 115 threading-block having a thread-passage leading to said eye, a member normally extending across the entrance to said passage, a cutting-blade, and means to move said blade relative to said member upon the occurrence of a float in the warp whereby the thread is severed. 120

9. In a loom-shuttle having a delivery-eye, a 125 threading-block having a thread-passage leading to said eye, a forked member normally extending across the entrance to said passage, a cutting-blade, and means to move said blade relative to said member upon the occurrence of a float in the warp whereby the thread is severed.

10. In a loom-shuttle having a delivery-eye and a thread-passage leading to said eye, a 130

pivoted member occupying a position above the thread in said passage, a cutting-blade below the same, and means to move said member and blade toward each other upon the occurrence of a float in the warp whereby the weft-thread is severed.

11. In a loom-shuttle having a delivery-eye, a thread-passage leading to said eye, a pivoted forked member situated above the thread, a pivoted float-detector having a cutting-blade occupying a position below the thread, said pivoted forked member having a portion to be engaged by the float-detector when the latter is operated by a float in the warp, whereby by said forked member moves toward the cutting-blade.

12. In a loom-shuttle having a delivery-eye, a threading-block having a thread-passage leading to said eye, a forked gate normally closing the entrance to said passage, a float-

detector having a blade to coöperate with said forked gate to sever the thread upon the occurrence of a float in the warp.

13. In a loom-shuttle having a delivery-eye, a threading-block having a thread-passage leading to said eye, a forked gate normally closing the entrance to said passage, a pivoted float-detector having one end bent to occupy a position beneath the thread-passage, whereby the occurrence of a float in the warp moves the bent portion of the float-detector toward the gate and thus severs the weft.

In testimony whereof I have signed my name to this specification in the presence of two subscribing witnesses.

JOHN C. BROOKS.
